METHOD OF AND MACHINE FOR PRINTING
CALENDARS

John C. Wahl, Chicago, Ill.

Application May 28, 1943, Serial No. 488,815

20 Claims. (Cl. 101—80)

This invention relates to printing machines more particularly intended for the printing of calendars to be made up in pad form, and to a method of printing and stacking the sheets from which said pads are made up.

Heretofore it has been the practice to simultaneously print a number of calendar sheets bearing the same date and place them in a separate pile or stack. When all of the different sheets covering a whole year have been printed, or when a number of them have been printed, the calendars are made up by taking a sheet from each different pile until a complete calendar pad has been built up.

This method involves a considerable amount of labor, and unnecessary handling of the individual sheets of the pad, often resulting in that many of the sheets become too soiled for use and have to be discarded.

It is an object of the present invention to provide a machine which will avoid the above-referred disadvantages and which will accordingly effect a saving in labor, the soiling of sheets and the resultant wastage.

A further object of my invention is to provide a machine adapted to continuously and automatically print and stack calendar sheets in proper sequential order.

Another object of my invention is to provide a continuous method for printing and stacking calendar sheets in sequential order.

With the above and other objects in view which will become apparent as the description proceeds, the machine of the invention is provided with means whereby the required data can be printed on each sheet, new data being automatically brought into position for each succeeding sheet as the paper on which they are printed passes through the machine.

In the accompanying drawings, which illustrate by way of example one embodiment of the invention—

Fig. 1 is a side elevation of the machine of the invention shown in the printing position;

Fig. 2 is a similar view to Fig. 1 showing the parts in another position;

Fig. 3 is a plan view of the machine;

Fig. 4 is an end elevation of the discharge end of the machine;

Fig. 5 is a partial side elevation of the side of the machine opposite to that shown in Fig. 1;

Fig. 6 is a section taken generally along the line 6—6 of Fig. 1;

Fig. 7 is a section taken generally along the line 7—7 of Fig. 3;

Fig. 8 is an enlarged detailed plan view showing the chain, certain of the printing heads, and associated parts for operating the heads;

Fig. 9 is a sectional view of the parts shown in Fig. 8, taken on the line 9—9 thereof;

Fig. 10 is a detailed section illustrating the mechanism for operating certain of the printing heads;

Fig. 11 is a similar view to Fig. 10 showing the mechanism in a different position;

Fig. 12 is a sectional view illustrating the mechanism for operating certain other of the printing heads;

Fig. 13 is a similar view to Fig. 12 showing the mechanism in a different position;

Figs. 12a and 13a are views corresponding to Figs. 12 and 13, respectively, but showing mechanism as embodied in the machine for printing calendars on leap years;

Fig. 14 is a section illustrating the mechanism for operating certain further of the printing heads;

Fig. 15 is a similar view to Fig. 14 showing the mechanism in different position;

Fig. 16 is a cross-section taken generally along the line 16—16 of Fig. 8;

Fig. 16a is another cross-section of the mechanism of Fig. 8, on the line 16a—16a thereof;

Fig. 17 is a detailed section of one set of cutting dies taken generally along line 17—17 of Fig. 18;

Fig. 18 is a section taken along the line 18—18 of Fig. 17;

Fig. 19 is an elevational view of the hopper-actuating mechanism;

Fig. 20 is a similar view to Fig. 19, but showing the parts in another position;

Fig. 21 is a plan view showing the intermittent driving mechanism for the paper feed;

Fig. 22 is a side elevation of the parts shown in Fig. 21;

Fig. 23 is a sectional view of the various types of printing heads, including two juxtaposed heads in combined form;

Fig. 24 is a face view of one of the calendar pad sheets produced by the present machine;

Fig. 25 is a diagrammatic view of the machine, illustrating the sequence of operations; and

Fig. 26 is a plan view of a strip of paper illustrating the operations performed thereon by the machine of the invention.

This application is a continuation-in-part of my co-pending application, Serial No. 377,227, filed February 3, 1941, and entitled Method of and machine for printing calendars.

General arrangement

The general arrangement of the machine of the present invention will be first described and this can be best done by referring to Figs. 24, 25 and 26 of the drawings.

Fig. 24 shows one sheet A of a calendar pad printed according to the present invention, it being noted that this sheet, similar to every other sheet necessary to make up the pad, is rectangular in shape, has a plurality of spaced lines B extending transversely thereof, a current month block C printed to one side thereof, and a past and succeeding month block D printed at the opposite side of the sheet, whilst disposed between the blocks C and D is printed the day E of the month in numerals and the name of the day of the week F. G are the usual holes by means of which the sheets are held in place by any suitable means and which are made in the course of the passage of the sheets through the machine as will hereinafter appear.

Turning now to Figs. 25 and 26, the main frame H of the machine is carried as usual by suitable supports I, and the paper P, which is in the form of a continuous strip and of any suitable stock, is fed on to the bed plate of the machine at the right hand end and first passes beneath the liner L where the lines B are drawn thereon. The paper strip P in its forward movement next passes beneath the printing heads or wheels J carried by a pivoted superstructure K which comprises a pair of vertically disposed plates, one disposed at each side of the main frame H of the machine. There are four of these heads for each calendar being printed (see Fig. 3), one of these J¹ printing the current month block C, the next J² printing numerically the day of the month E, the third J³ the day of the week F and the fourth J⁴ printing the past and succeeding month block D. Incidentally, here it should be mentioned that the machine shown in the drawings is designed to print four sets of sheets transversely of the same continuous strip of paper P simultaneously, as will be clear from Figs. 3 and 26, but it is to be understood that the machine may be modified to print a smaller or a greater number of identical sheets at one and the same time.

After the printing the paper strip proceeds to the cutting mechanism M which cuts the sheets A from the strip P and from whence they pass to the conveyor N and finally pass to and are collected in the hopper O. The hopper is divided into a plurality of compartments O¹, and as the machine prints the sheets in consecutive date order it will be seen that by retaining the hopper in the same position until 365 sheets have been printed—or 366 in case of a leap year—a complete calendar pad with the sheets in correct sequence can be built up in that compartment O¹ which is juxtaposed to the conveyor N.

R illustrates diagrammatically the inking mechanism for the printing heads.

The printing heads

All of the printing heads are mounted on a shaft 2 (see Figs. 1 and 2), the ends of which are carried by the superstructure K. All of the various heads J⁴ are fixed to the shaft 2 for rotation therewith, as are also all the wheels J¹, the juxtaposed intermediate wheels J¹ and J⁴ being (see Fig. 3), in fact, formed as one wheel, as shown in Fig. 23, whilst the one outside wheel J¹ (see Fig. 3) and the one outside wheel J⁴ at the opposite side of the machine are single wheels.

Each of the heads J¹, which prints the current

month block C on the paper strip, carries twelve plates 4, Fig. 7, one plate, of course, for each month of the year.

Each of the heads J⁴, which prints the past and succeeding month block D also has twelve plates 4 (see Figs. 8, 10 and 11), each carrying data of the month preceding and of the month succeeding the month being printed.

All of these heads J¹ and J⁴ are driven with the shaft 2 to which they are fixed, from means attached to the outside wheel J⁴ and which means takes the form of a circular plate 6 having twelve notches 8 provided therein and a ratchet wheel 10 in the circumference of which is disposed twelve teeth 12.

The revolution of the said wheels J¹ and J⁴ is brought about by the engagement with the said teeth 12 of a plunger arm 14, the opposite end of which is pivoted to an arm 16 fixed to an operating shaft 18. The movement of the arm 16 to bring about the forward movement of the plunger and in turn the step-by-step rotation of the wheels J¹ and J⁴, is effected by the raising of the superstructure K, as will hereinafter be described, through the intervention of a depending arm 20 connected to said shaft 18 and having at its lower end a pin 22 which projects through a slot 24 in one side of the superstructure K. (See Fig. 2.)

The heads J² which print the days of the month in numerals (see Figs. 8, 14, and 15) are each provided with thirty-one peripheral portions 26, each bearing consecutively the numbers one to thirty-one, an equivalent number of teeth 28 being formed in a ratchet wheel 30 attached to each head J². Each head J² has a step-by-step motion imparted to it through the instrumentality of said teeth by means of a plunger 32 pivotally connected to an arm 34 which in turn is fixed to the shaft 18. There are four arms 34 on the shaft 18, and four plungers 32 (see Fig. 3), one for each of the four heads J². The heads J² are loosely mounted on shaft 2, and are individually actuated by their respective arms 32. Between the portions 26 on each head J² are formed notches 35, the purpose of which will hereinafter appear.

The heads J³ which print the days of the week (see Figs. 8, 12, and 13) are each provided in the present instance with twenty-eight types 36, which consecutively carry indications of the days of the week—Sunday, for example—and have fixed thereto a ratchet wheel 38 having an equivalent number of teeth 40, whilst between the types 36 in each head J³ are formed notches 42—the latter for a purpose to be explained later.

The step-by-step rotation of each of heads J³ which are loosely mounted on shaft 2, is effected by means of an associated operating member or plunger 44 pivotally connected to and actuated by the same arms 34 on shaft 18, which also operate plungers 32 for heads J².

To effect the printing of calendars on leap years special operating plungers 44a, as shown in Figs. 12a and 13a, are provided, and substituted for the plungers 44, for actuating the heads J³, as will be later described.

Having thus described the construction of the various printing heads and their respective functions, the mechanism for rotating said heads in order to advance succeeding plates to the printing position at the proper time or intervals will now be explained.

The superstructure K, which is pivoted to the main frame H of the machine at 44 (Fig. 1) is provided with an extension in the form of a plate 76 K¹ (Figs. 1, 2, and 3) at one side of the machine;

and carried by a plurality of sprocket wheels 46 rotatably mounted on said plate in an endless chain 48 normally consisting of 365 links—the equivalent of one for each day of a normal year. When printing leap year calendars an additional link is added to the chain.

The machine is driven from any suitable source of power such as an electric motor 50, which, through a belt 52 drives a shaft 54, on which at opposite sides of the machine is mounted a cam 56. Each side plate of the superstructure K has a downwardly extending portion 58 (Fig. 2), which carries a roller 60 engaging the cam 56. The contour of the cam is such that it will raise the superstructure K and maintain it raised and then allow it to return to its lowermost position more or less suddenly.

Adjacent and fixed to the upper left-hand sprocket wheel 46 carrying the chain 48 (see Figs. 8 and 9) is a ratchet wheel 62 to which is imparted a step-by-step movement through the instrumentality of a plunger 64 which is connected to the actuating arm 16 fixed to the shaft 18. Plunger 64 is pivotally connected to the arm 16 by means of a pin 66 extending through a slot 68 in one side of the superstructure K. Thus as the ratchet wheel 62 is rotated, the chain 48 is moved forwardly link by link. Arm 16 operates both the plunger 14 and the plunger 64.

Pivoted on one side of the main frame H at 70 (see Figs. 2 and 3) is a curved arm 72, which is in turn pivotally connected at 74 to a second arm 76 pivoted at 78. The opposite end of the second arm 76 is provided with a slot 80 in which engages a pin 82 carried by one arm of the bell-crank lever 84 pivoted to the superstructure K at 86, and the other arm of which bell-crank lever 84 is provided with a U-shaped slot 88 for engaging pin 22.

Also mounted on the pivot 78 is a star wheel 90, which is adapted to be operated by a spring-pressed pawl 92 carried by the arm 76. As the superstructure is raised by the action of the cam 56, the arm 72 being fixed by its pivot 70 causes the second arm 76 to be rotated on its pivot 78 and through the medium of pawl 92 causes the rotation of the star wheel 90 counterclockwise in Fig. 1. The teeth of the star wheel engage a pin 94 which projects into its path through a slot 96 in the superstructure K, this pin being attached to arm 98 fixed to and depending from a detent shaft 100 (see Fig. 7, for example).

The shaft 100 extends transversely across the machine (see Fig. 3) and at intervals is provided with detents, one detent 102 being provided to control the outside printing head J⁴, and hence through it the remaining heads J⁴ and all of the associated heads J¹; further detents 104 being provided to control each of the printing heads J², and still further detents 106 being provided to control each of the printing heads J³.

All of the detents are fixed to shaft 100 and normally engage their respective notched heads, being held in this position by means of a spring 108 (Fig. 7) attached at one end to the arm 98, and at the other end to a pin 110 projecting from the superstructure K.

When the superstructure K is raised, as hereinbefore described, the star wheel 90 is turned by its pawl 92 and the pin 94 is then pushed from the right-hand side of the slot 96 to the left-hand side, this operation moving the arm 98 against the action of the spring 108 from the right to the left (see Fig. 7) and this in turn releasing the detents from engagement with the teeth of their

respective ratchet wheels, leaving the printing heads then free to be rotated or indexed by their plungers.

The pivoting of the second arm 76 about its pivot 78 simultaneously causes the bell-crank lever 84 to be moved from the position shown in Fig. 1 to that shown in Fig. 2, this movement moving the pin 22 from the left-hand side of the slot 24 to the right-hand side thereof, this action, of course, also moving the arm 20 attached to the shaft 18 in like direction, and causing the various plunger arms to be moved forward, or to the left in Fig. 7, for example. As to whether this forward movement of said plungers will be effective to rotate their respective printing heads or not is determined by means which will hereinafter be described.

It will be noted that the movement of the pin 22 is brought about by its engagement in the U-shaped slot 88 of the bell-crank lever 84. The left-hand leg of the U is made slightly shorter than is the right leg thereof, with the result that after the pin 22 reaches the right-hand extremity of the slot 24 the pin having just left the slot 88, the said shorter leg can move underneath the pin and thus hold the pin in this position and still permit further travel of the bell-crank arm as the superstructure K continues to rise, this causing a "dwell" in the movement of the actuating plungers to hold the printing heads in position and provide time for the teeth of the star wheel to disengage the pin 94 and allow the detents 102, 104 and 106—under influence of the spring 108—to snap back into engagement with the teeth of their notched wheels and thus lock the printing heads in position before the actuating plungers are released from engagement therewith.

Control of printing head rotating mechanism

Printing heads J¹ and J⁴ are rotated by means of the single plunger 14 (see Figs. 8, 10, and 11). Plunger 14 is normally held in a raised inoperative position by means of pin 112, carried at the outer extremity of one arm of a bell-crank lever 114 rotatably mounted on the reduced portion 116a of a shaft 116 (see also Fig. 16), the outer extremity of the other arm of said bell-crank lever being also provided with a pin 118 which engages a slot in the outer extremity of one arm of a second bell-crank lever 120, rotatably mounted on a shaft 122 carried by the superstructure K.

As has hereinbefore been stated, the endless chain 48 is provided with 365 links (or 366 links on leap year) and is adapted to be rotated one link at a time by means of the plunger 64. The position of the printing heads J¹ and J⁴ has only to be changed after all the sheets for any particular month have been printed—that is to say, if sheets for the month of June have just been printed, then the printing heads J¹ and J⁴ must be moved one step forward in order that the monthly data provided by these heads is changed for the printing of sheets for the month of July. The position of such heads will not again have to be changed until a sheet has been printed for every day in July—that is to say, until the chain has been moved thirty-one steps forward. Every time a sheet is printed, however, the plunger 14 is moved forwardly, but as has been explained, is kept raised by the pin 112 so that its forward thrust will not rotate the printing heads J¹ and J⁴.

To allow the forward movement of the plunger to be effective at the times desired—that is to say, on the completion of the printing of sheets for

each individual month—the chain 48 is provided at spaced intervals and at one side with upstanding ears, or lugs, 124. As these ears or lugs move forward, at the appropriate times they come into contact with a pin 126 projecting into their path from the other arm of the said second bell-crank lever 120. The result is that said arm is raised and through the other arm of this bell-crank 120 and its associated bell-crank 114, the pin 112 is allowed to drop in its slot 113, with the result that the plunger 14, now being in its lowermost position, on its stroke forward will engage one of the ratchets 12 on the ratchet wheel 10 associated with the head and turn the latter through one-twelfth of its revolution and thus bring new printing plates on heads J¹ and J⁴ containing data for the month about to be printed into position.

After the ear or lug 124 has passed under pin 126 the bell-cranks 120 and 114 will be restored to their normal position by the spring 128, and thus cause the pin 112 to restore the plunger 14 to its ineffective position.

The tops of the ears 124 are preferably sloped as shown so as to facilitate the raising of the pin 126 thereover.

The ratchet wheel 62 on each operation of the machine is held in the position to which it has been moved by the plunger 64, by means of a spring-pressed pawl 125 (Fig. 9).

In like manner the changing of the printing heads J² (see Figs. 14-15), which print the days of the month, has to be controlled and this is done by the employment of a plurality of ears 130, spaced along the chain 48 on the side opposed to that on which the ears 124 are spaced, as shown in Fig. 16. The problem here, however, is a little different, because each of the four plungers 32 must normally make contact with its ratchet wheel 30 in order to move the associated printing head J² one step forward every time a new sheet is to be printed. In the case of sheets being printed for a month having thirty-one days, each plunger will thus contact its ratchet wheel 30 thirty-one times consecutively, as in the case when printing sheets for the month of January. After sheets for this month have been printed, each plunger 32 is allowed to continue to contact and rotate its ratchet wheel 30 twenty-eight times, but then must skip the three remaining places, corresponding to the 29th, 30th and 31st days. This control of the plungers 32 is brought about by means of a bail or shaft 132 (Figs. 3, 8, 14 and 15), extending across the machine, said bail being carried by a pair of arms 134 fixed to the shaft 116. Shaft 116 has fixed to its end an arm 135 (Fig. 16), the extremity of which is provided with a pin 138 which engages a slot in the extremity of one arm of a bell-crank lever 140 pivoted on the shaft 122, the other arm of said bell-crank lever being provided with a pin 144 adapted to be contacted and raised by the ears 130. The bail 132 normally holds each of the several plungers 32 in such position that on its forward stroke it will move its ratchet wheel one step forward. When, however, it is desired to skip three days, as at the end of February, then the chain is provided with an ear 130, of such height that when it contacts the pin 144, it will operate the bell-crank lever 140 so as to drop the shaft 132 to such an extent that the plungers 32 will drop three notches—or from the 28th to the 1st—so that on the forward stroke of said plunger, the printing head J² associated there-

with will be moved forward not one step, as is usual, but three steps.

Likewise, in the case where the 31st plate is to be ignored, for example, at the end of June, then the chain will be provided with an ear of such a height that when the pin 144 is actuated thereby, the plungers 32 will only be dropped one notch and hence on their next forward movement will change the heads J² from the 30th to the 1st.

10 It will be appreciated that, in so far as concerns the heads J¹, J⁴, and J², the present machine can easily be modified to take care of the extra day at the end of February in a leap year by adding one link to the chain and substituting 15 for an ear which will provide a three-day skip at the end of February, an ear which will furnish but a two-day skip—that is to say, will turn the printing heads J² after the printing of the sheet for the 29th of February so that they will next print the sheet for the 1st of March.

20 The printing heads J³ which print the names of the days of the week, must be rotated one step at each operation of the machine throughout the printing of the dates for the entire year, and this 25 is true whether the year being printed is a leap year or a non-leap year. However, when the last date of the year has been printed—December 31st—special operation is necessary to effect the proper printing of the sheet for the first day of 30 the year, as the yearly sequence is reprinted for the next calendar pad. More specifically, if the calendar pad being printed is for a non-leap year, it will be found that the last day of the year is the same day of the week as the first day of said 35 year. Accordingly, as the printing of one calendar pad is finished, and the next one begun, for the same year, it is necessary that the heads J³ be retained in fixed position between the printing of December 31st and the succeeding January 1st, 40 so that they will effect the printing of the same day of the week for both dates. In the case of leap years, it will be found that the first day, or January 1st, of any given leap year is one day of the week earlier than the last date, December 31st, of said year. For example if December 31st of a leap year is Thursday, January 1st of that year will be Wednesday. Accordingly, in effecting the successive printing of calendar pads for leap years, it is necessary that the heads J³ be 45 stepped backward one step when successively printing the dates of December 31st and January 1st, so as to effect the proper day of the week printing operations. The mechanisms for effecting the proper operation of the day of the week 50 printing heads J³ will now be described.

55 As previously indicated, the four heads J³ are loosely mounted on the machine cross shaft 2, and are independently actuated by their respective operating plungers 41. Each head contains twenty-eight printing blocks arranged successively 60 in four day of the week printing sequences. Obviously printing heads having any number of printing blocks, in multiples of seven, may be employed. The mechanisms for operating the heads J³, in printing non-leap years, are illustrated in Figs. 12 and 13, when taken with the other drawings, with the exception of Figs. 12a and 13a. Figs. 12a and 13a illustrate the mechanisms which are substituted in the machine to 65 effect the operation of the heads J³ during the printing of leap year calendars.

70 Referring to Figs. 12 and 13, and also Figs. 3 and 8, it will be seen that the operating plungers 41 for operating the ratchet wheels 38 secured, 75 respectively, to the printing heads J³, are pro-

vided with tail extensions 127 extending rearwardly of the pivotal connection between the plungers and their operating levers 34. These rearwardly extending tail extensions bear against the underside of a bail shaft 129 extending across the machine, which bail shaft is supported on a pair of arms 131 secured to a cross shaft 133 journaled in the two side plates of the superstructure K. The shaft 133 extends through one wall K and has secured to its end an arm 136, Fig. 16a, provided at its extremity with a pin 137 adapted for cooperation with a lug or ear 139 carried at a given point on the chain 48. This lug or ear 139 projects downwardly from the chain along one of its side edges, in the opposite direction from the lugs or ears 138 previously described. A tension spring 141 anchored at one end to one of the arms 131, and at its other end to a pin 142 projecting from the frame K, normally holds the bail shaft 129 in its uppermost position, as shown in Fig. 12, with the arm 136 in engagement with a stop pin 143, also carried by the frame K.

In operation, normally and while the calendar sheets for each day of the year are being printed, at each operation of the machine the several operating plungers 41 are projected forwardly at each operation of the shaft 18, to move the several ratchet wheels 38 and heads J³ forwardly one step, thereby effecting sequential day of the week printing throughout the year. At this time the bail 129 remains at its uppermost position, as illustrated in Fig. 12, so that the tail extensions 127 remain sufficiently elevated to permit the forward ends of the operating plungers 41 to operatively engage the teeth 40 of the ratchet wheels. However, after the date of December 31st has been printed, and as the machine is then again operated to effect the printing of the January 1st sheet for the succeeding calendar pad, the lug 139 is brought into engagement with the pin 131, as the chain 48 is operated, and as shown in Fig. 13, so that on the forward operation of the plungers 41, their tail extensions are depressed by the bail 129 lifting the forward ends of the plungers and causing them to be inoperative to effect the operation of the ratchet wheels for the heads. As will be understood, the chain is provided with but a single lug 139, operative once in the printing of each calendar pad.

Referring to Figs. 12a and 13a, it will be seen that to effect the printing of leap year calendars plungers 41a, of somewhat different form from the plungers 41, previously described, are substituted. The plungers 41a are also pivotally connected to the several actuating arms 34, for operation thereby, but are connected to the arms at a point further spaced from the shaft 18, so that on operation of the arms 34 the plungers 41a will be projected forwardly a distance corresponding to two steps of actuation for the ratchet wheels 38 and their associated printing heads. The tail extensions 127a of the plungers are also differently shaped, as shown, and in this instance cooperate with a bail shaft 129a supported by a pair of arms 131a secured to the shaft 133. The shaft 133 is provided on its end with its operating arm 136, previously described, carrying the pin 137 for engagement with the chain lug 139a similar in function to the lug 139 previously described, but arranged to effect its particular operations. In this instance the restoring spring 141a and the frame pin 142a to which the anchor end of the spring is connected are somewhat differently arranged and connected to the arm 131a, as shown.

Accordingly, it will be seen that to effect the printing of leap year calendars only the differently shaped plungers 41a, and the differently arranged bail assembly 131a—129a need be substituted, the other parts remaining the same. In Fig. 8 the location of the bail 129a is indicated in dot and dash lines.

One of the plungers 41a is provided with a downwardly extending projection 145 cooperable with a lever 146 secured to the detent carrying shaft 100. Also, it will be noted that the forward ends of the plungers 41a are provided with a pair of operating projections 147 and 148, the latter being in the form of a hook for cooperation with the hook-like shaping of the ratchet wheel teeth, as will now be described.

In operation, as stated, on each operation of the shaft 18 the plungers 41a are projected forwardly a distance corresponding to the actuation of two steps of the ratchet wheels 38a. However, the bail 129a is normally held at its lowermost position, as shown in Fig. 12a, so that the forward end of the plungers 41a are lowered only sufficiently to permit the plungers to engage one ratchet tooth, as indicated at 40a, whereby to effect a single step actuation of the ratchet wheel. In other words, the forward ends of the plungers are not lowered sufficiently to engage the ratchet tooth, as indicated at 40b. Accordingly, at each operation of the machine the ratchets 38 and associated heads J³ are moved one step to effect the proper day of the week printing sequence.

After a complete calendar pad has been printed, and as the machine operates to effect the January 1st printing of the next calendar pad, the lug or ear 139 engages the pin 131 to effect the raising of the bail 129a. This engagement takes place upon operation of the chain 48, after the plungers 41a have moved sufficiently forward so that their operating portions 147 do not engage the ratchet teeth 40b. In other words, the plungers 41a are projected forwardly, and after their operating portions 147 have passed the ratchet tooth position, as indicated at 40b, the bail 129 is raised permitting the forward ends of the plungers to drop into engagement with the ratchet teeth. Accordingly, on this operation of the machine the ratchet wheels will be stepped forwardly one step, as in normal operation, but as the plungers 41a are withdrawn, the hook-like portions 148 thereof catch the ratchet wheel teeth, as indicated at 40c, and effect a reverse operation of the ratchet wheels. In view of the extended travel of the plungers 41a, this reverse actuation moves the ratchet wheels and associated printing heads two steps backwardly, so that by the time the frame K has been lowered into printing position, and the reverse movements of the heads J³ are completed, the heads will have been moved backwardly one step from the position that they occupied during the previous printing operation. During this reverse movement the arm 145, provided on one of the plungers 41a, engages the arm 146 and rotates detent shaft 100 counterclockwise against the action of spring 108 to withdraw the detents from the notches of the printing heads whereby to permit the heads to be shifted or indexed. The length of the arms 145 and 146 is so predetermined that the arm 146 is released just prior to the time that the plungers 41a complete their reverse travel, whereby to release the detents for engagement with the printing heads to prop-

erly position and hold them for the printing impact.

On the next forward operation of the machine, as the chain 48 is actuated, the lug 139 leaves the pin 137 causing the bail 129a to be restored to its lowermost position; and this action takes place during the initial forward movements of the plungers 41a, so that the forward ends of the plungers are lifted over the ratchet teeth, as indicated at the position 40b, and engage only the ratchet teeth as indicated at the position 40a, whereby to effect the forward movement of the ratchet wheels one step, as required.

Instead of using an endless chain arrangement for doing the work above described, I may also use a wheel with 365 or 366 peripheral teeth or notches combined with lugs to represent each month to act the same as the lugs on the chain.

The lining mechanism

Coming now to the lining mechanism L, reference may be had to Figs. 1, 2, 3 and 4. As previously explained, a strip of paper is fed into the machine from the right hand end and travels underneath a lining mechanism. This mechanism comprises a frame 150 carried by a pair of forwardly extending arms 152, one at each side of the main frame H and pivoted to the latter at 154. Mounted on guides 156 within the main frame 150 is a pen-carrying frame 158 carrying a number of pens 160 divided into two banks, one at each end of the frame 158. The main frame 150, carrying with it the pen-frame 158 and pens 160, is raised and lowered by means of a pair of cams 162, one located beneath and engaging each of the two supporting arms 152, thus bringing the pens alternately into and out of engagement with the paper P. The pen-frame 158 is moved back and forth across the machine on the guides 156, and hence transversely of the paper by means of a link-work 164 at one end pivotally connected to cross-bar 166 and at the other end to a bar 168 projecting from one side of the main frame H. A roller 170 on one of the links of the link-work 164 is held in engagement with a cam 172 having a sloping face 174, by means of a spring 176, the cam 172 being mounted on the same shaft 178 as is the cam 162 which raises and lowers the frame 150.

As the pen-frame 158 is moved across the machine in one direction, it is in its raised position. For the return movement, however, the frame is lowered, which brings the attached pens 160 into contact with the paper P to produce the lines thereon. Two banks of pens are provided so as to shorten the length of the stroke of the pens of the individual banks.

The shaft 178 carrying the cams 162 and cam 172 is driven from the main shaft 54 of the machine (see Fig. 6) by means of a chain 180 and sprocket wheels 182 and 184.

The intermittent drive for the paper, etc.

Mounted on the end of the main shaft 54 (see Figs. 1, 6, 21 and 22) is a segmental gear 190 and directly behind the segmental gear and secured thereto is a plate 192. Segmental gear 190 meshes with a gear wheel 194 mounted on a stub shaft 196 and directly behind gear 194 and secured thereto and in line with plate 192 is another plate 198. The plate 192 has a pair of notches 200, 200a formed therein, which cooperate with a pair of projections 202, 202a on plate 198.

As the segmental gear 190 is rotated by shaft 54 a leading tooth 190a engages one of the teeth

on gear 194 and starts the rotation of gear 194 and plate 198. At this instant the notch 200 in plate 192 is in a position to receive one end of the projection 202 so as to permit the rotation of gear 194 and plate 198. Upon continued rotation of the gear 190 each successive tooth on gear 190 engages successive teeth on gear 194 until the last tooth 190a on segmental gear 190 disengages the teeth of gear 194.

At this time the other notch 200a in the plate 192 is in a position such as will permit the projection 202a of plate 198 to move into engagement with the plain portion of the disc 192, thus preventing the gear 194 from rotating until the leading tooth 190a again comes into engagement with a tooth on gear 194. It will be appreciated that the curvatures of the plain portion of the gear 190 and of the projections 202, 202a permit the gear 190 to continue its rotary motion, the gear sliding past that projection then in engagement therewith whilst the gear 194 remains stationary.

This arrangement thus provides an intermittent drive for the shaft 196 and in turn an intermittent drive for a sprocket 204 (see Fig. 3) mounted on stub shaft 196, this sprocket being provided with a chain 206 which engages another sprocket 208 mounted at one end of a shaft 210 which carries rollers 212 for feeding the strip of paper P through the machine. Also mounted adjacent the end of shaft 210 in front of sprocket 208 is another sprocket 214 which is connected through a chain 216 with another sprocket 218 mounted at one end of a second roller shaft 220 carrying rollers 222.

Mounted directly beneath the roller shafts 210 and 220 are further roller shafts 224 and 226 (Fig. 5), which also carry rollers which cooperate with rollers 212 and 222 and are frictionally driven through the intermediary of the paper passing between the sets of cooperating rollers. With this arrangement the paper strip is accordingly driven in an intermittent manner through the machine, thus providing proper stops during the required printing and so that the lines B can be drawn thereon.

The cutting mechanism

The next step in the operation of the machine is to cut the individual printed sheets from the strip of paper. In order to accomplish this (see particularly Figs. 4, 5, 6, 17 and 18), there is provided a plurality of female dies 230 arranged transversely of the machine on the main frame thereof, one die being provided for each calendar being printed—that is to say, as the present machine is capable of printing four separate sheets at one time, four female dies 230 are a corresponding number of male dies 232. The male dies are all conveniently attached to and depend from a frame 234, which in turn is guided by pins 238 which project upwardly through collars 236 disposed at the four corners of the frame.

The male dies 232 are raised and lowered by a pair of arms 240, one disposed at each side of the machine. The upper end of each arm 240 is pivoted to the frame 234 at 242, whilst the lower end of each arm is hollowed out to receive an eccentric disc 244 secured to a shaft 246 extending transversely of the machine. The rotation of the eccentric within the hollow base of the arm thus provides the necessary up and down movement of the male dies with relation to the female dies to perform the desired cutting operation.

Where it is desired to punch holes in the sheets

being printed for mounting purposes, there is provided (see Figs. 17 and 18) a pair of pins 248 mounted in a lip 250 formed in the advance end of each of the female dies 230. Spaced above the lip 250 is a plate 252 having in recessed portions holes for receiving the upper ends of the pins 248. The plate 252 which is free to move up and down in the die, is resiliently held in its upper position by means of springs 254 on the pins 248. The movement of the plate 252 beyond the upper edge of the die is prevented by a pair of screws 253 screwed into the lip 250 and having their heads disposed in recesses in the plate 242. The male die 232 has a pair of holes 256 in line with the pins 248. Upon the downward motion of a male die 232 it comes into contact with the paper and presses the paper against the plate 252 and on continued downward motion causes the plate 252 also to move slightly downward within the female die 230, against the pressure of the springs 254, thereby causing the pins 248 to protrude through the paper and into the holes 256 in the male die. At the same time, of course, the male die also serves the rectangular calendar sheet from the paper strip P.

It is to be noted that the holes 256 in the male die have a portion of reduced diameter adjacent their lower ends for cutting the holes in the paper of the required size. Above this, said holes are of increased diameter so that the small round pieces of paper cut out during the cutting operation can move freely upward therethrough and thus avoid choking of the dies.

When the cutting operation has been completed and the male dies have returned to their uppermost positions, it is necessary to provide means for pushing the cut sheets through the female dies past the hole cutting mechanism after which they will fall by gravity onto the conveyor N. To accomplish this there is provided a rectangular plate 258 (see Fig. 17) mounted in a recess 260 in the underside of each male die. Each rectangular plate 258 is secured to the lower end of a rod 262, the rod 262 having a bearing 264 on the upper side of the plate 234. At the upper end of rod 262 is a pin 266 (see Fig. 5) which engages a U-slot 268 at one end of an arm 270, the opposite end of which is secured to a shaft 272. The shaft 272 extends transversely of the machine bearing at its ends in a pair of upwardly extending supports 274 secured to the main frame H.

Upon oscillating the shaft 272 by the means hereinafter described, the outer ends of the arms 270 are raised and lowered, carrying with them the rods 262, thus causing the rectangular plates 258 to extend down into the female dies pushing the individual calendar sheets ahead of them past the hole cutting mechanisms. It will, of course, be appreciated that one arm 270 and its associated mechanism is provided for each male die but all of these arms are operated through the medium of but one arm 276 secured at one side of the machine to the shaft 272. To the outer end of this arm 276 there is attached a downwardly extending connecting rod 278, to the lower end of which is pivoted a lever 280 pivoted at 282. This arm is provided with a downwardly extending claw-like arm 284. Also pivoted at 282 and secured to the back of arm 280 (see Fig. 5) is an upwardly extending claw-like arm 286. Mounted on one end of the shaft 246 is a disc 288 from one face of which projects a pin 290 to cooperate with the lower claw arm 284, whilst from the

other face of the disc 288 projects a pin 292 to cooperate with the upper claw arm 286.

As seen from Fig. 5, upon continued rotation of the disc 288 the pin 292 will contact the upper arm 286 and will cause said arm to be raised, thereby causing arm 284 and arm 280 to be rotated about their fulcrum 282 causing the arm 278 to be pulled in a downward direction which in turn will pull down the arm 276 and impart a downward motion to the shaft 272. Upon continued rotation of the disc 288 pin 292 leaves the upper arm 286, whilst the pin 290 engages the lower arm 284, pushing it downwardly and reversing the motion of the parts above described.

To provide power for the movement of the male dies with respect to the female dies and for the means which push the cut sheets through the female dies (see Fig. 6) on the main shaft 54 is mounted a sprocket wheel 294 which, through a chain 296, drives a sprocket 298 mounted on a shaft 300 having its bearings in the main frame H. On the shaft 300 is another sprocket wheel 302 which, through a chain 304 and a sprocket 306, drives the shaft 246, thus imparting motion to both the eccentric 244 and the disc 288 fixed thereto.

The conveyor drive

Mounted on the end of shaft 196 (see Figs. 1, 2 and 3) is another sprocket 310, which through a chain 312 and a sprocket 314 mounted at one end of a shaft 316, drives the conveyor N, the shaft 316 extending transversely of the machine and having its bearings in the main frame H. By this drive an intermittent motion is imparted to the conveyor N which comprises, in the present showing, an endless band adapted to be carried by a pair of rollers 318, the rear roller being disposed on the shaft 316 on which the sprocket wheel 314 is mounted.

The conveyor N is positioned directly underneath the female dies 230 so that upon the punching out of a sheet from the paper strip P, it falls onto the conveyor and is carried forward thereby to be deposited into the juxtaposed compartment O³ of the rotary hopper O. The hopper O remains stationary throughout the printing of sheets for a full year's calendar and at the end of said printing is automatically rotated to bring the next compartment O³ into position by the mechanism which will now be described.

The hopper drive

Referring more particularly to Figs. 5, 6, 19 and 20, it will be seen that mounted upon the end of a stub shaft 320 is a sprocket 322 which drives the hopper O through a chain 324 and a sprocket 326 mounted on the hopper shaft 320. On plate 328 mounted on the shaft 320 between the sprocket 322 and the main frame H is a series of equally spaced-apart pins 330. Pivotedly mounted on one of the cams 56 as by a screw, is a link 332, which at its opposite end is pivotally connected to an arm 334, which in turn is rotatably mounted at its lower end 336 to the main frame H. Pivotedly secured to the upper end of arm 334 is an arm 338 which is held in a raised position by means of a spring 340 and which towards its opposite end bears against a pin 342 mounted on an arm 344, pivoted at 346 to the main frame H. The arm 344 is normally held in its uppermost position with its tail-piece 352 in contact with a stop 350 by means of a spring 348. The opposite end of arm 344 has a portion 354 extending upwardly adjacent one side of the chain 48. Secured to the

side of the chain 48 is a pin 356 (see Fig. 16) to cooperate with the upward extending portion 354 of the arm 344. Secured to the arm 344 is a square stud 358 which cooperates with a notch 360 in one finger 362 of a bell-crank 364 pivotally secured at 366 to the main frame H, the other finger 368 of a bell-crank 364 projecting downwardly adjacent the periphery of the cam 56. The bell-crank 364 has a spring 370 which tends to rotate the bell-crank in a clockwise direction, causing the finger 362 to rest on the upper side of the square projection 358.

As hereinbefore indicated, the hopper O has to be rotated to bring a new compartment thereof into operative position with respect to the conveying mechanism only after the sheets constituting a full year's calendar have been printed. Accordingly, the chain is only provided with one pin 356 and when this comes into engagement with the upwardly projecting portion 354 of the arm 344, the mechanism just described will operate as follows to bring the next succeeding compartment of the hopper into the desired position.

The pin 356 engages the upwardly extending portion 354 of the arm 344 and causes the latter to be rotated in a counterclockwise direction against the pressure of the spring 348. As the arm 344 moves about its pivot the pin 342 presses the arm 338 downwardly. As the arm 344 moves, it carries the square projection 358 to the cam finger 362 which slides over the top of the projection 358, the downward pull of the spring 370 on the bell-crank 364 aiding in the operation. As the cam finger 362 slides over the square projection 358, the notch 360 engages the projection, thus locking the parts in this position so that when the pin 356 has passed over the upward extending portion 354, the springs will be unable to return the arms 338, 344 and the bell-crank 364 to their normal positions.

As the cam 56 rotates with the said arms in their locked position, it causes the link 332 to move the upper end of the pivotally mounted arm 334 to the right, causing the vertical face 372 of the arm 338 to engage one of the pins 330 (see Fig. 20) and rotate the disc 328 a predetermined distance about its fulcrum 320. This causes the sprocket 322 through the chain 324 and sprocket 326 to rotate the hopper to bring the next compartment into position to receive the calendar sheets from the conveyor.

As the arm 334 nears the end of its stroke, it engages the cam finger 368 of the bell-crank 364 and disengages the notch 360 from the square projection 358, thereby allowing the arm 344 and the bell-crank 364 to return to their rest positions. At this time, however, the stroke of the arm 334 is not quite complete and the arm 338 must therefore still be retained in engagement with the pin 330 so that the correct amount of rotation will be transmitted to the hopper O. For this purpose a pin 374 secured to the main frame H is provided, which the finger portion 376 of the arm 338 passes beneath as the arm 344 and bell-crank 364 unlock. The pin 374 thus keeps the arm 338 from returning to its rest position.

As the cam 56 continues its rotation, the arm 338 will be pulled to the left by means of the link 332 and the arm 334, so that when the finger 376 moves from under the pin 374, the spring 340 will return the arm 338 to its rest position and the parts will then once again be in proper position for the next operation. It will be understood that each time the cam 56 rotates, the arm 338 will be moved forward but ineffectively inso-

far as the pins 330 are concerned, as will be clear from Fig. 19, the arm merely moving backwards and forwards with a cam surface 378 on its upper side in contact with the pin 342; thus no motion will be imparted to the disc 328 except when the mechanism is actuated by the pin 356 on chain 48.

In order to maintain the hopper in the position to which it has been moved by the mechanism just described, on the hopper shaft 380 is fixed 10 a notched wheel 382 with which cooperates a spring-pressed detent 384.

The inking mechanism

The necessary inking of the type is effected by 15 a set of inking rolls 390, such as commonly known in the art. The rolls are moved across the type on each machine operation at the time the superstructure K carrying the printing heads, is in its raised position, as shown in Fig. 2. The inking rolls in their frame are carried across the type by a pair of arms 392 and 394, at opposite sides of the machine. The arms 392 and 394 are secured to a shaft 396 mounted in bearings in the main frame H. The shaft 396 is oscillated by means of an arm 398 secured thereto carrying 20 at its outer end a cam follower 400 engaging a cam groove 402 in a concentric cam 404 secured to the shaft 300. The shaft 300 is rotated, as previously described, carrying the cam, which in turn causes the shaft 396 and the arms 392 and 394 to oscillate by means of the arm 398 and cam follower 400. The inking rolls, on each reciprocation, engage the type plates in position for printing contact, and in the case of heads J² and J³, also the type adjacent the printing position.

The inking rotation of the rolls as they reciprocate may be effected by any well-known means, but in the drawings this is shown as being brought about by means of toothed wheels 406 adapted to 25 be rotated by a rack 408 in part carried by the superstructure K and in part by the upwardly extending supports 214.

Referring to Figs. 24 and 25, it will be understood that for actual commercial operation the 30 mechanism may be provided at a suitable place with a 45 mechanism for doing any suitable additional printing Q; for example, the name of the customer and advertising matter of the customer for whom the calendar is supplied. One suitable way of providing this means is to equip the superstructure K with a plate diagrammatically shown at Q¹ in Fig. 25 which cooperates with a suitable bed diagrammatically shown at Q².

The invention has been hereinbefore described 35 in connection with the printing of calendar pad sheets having certain specified data thereon; it is to be understood that such data can be varied as desired without departing from the spirit and scope of the invention in order to provide sheets 40 adapted to meet different requirements. This, as 50 will be readily appreciated, can easily be accomplished by merely substituting new plates containing data different from that hereinbefore described.

Further, the machine can readily be adapted 55 to print sheets other than calendar sheets—in fact, any sheet where succeeding sheets are to differ as to the data printed thereon from a preceding sheet.

The invention is hereby claimed as follows:

1. A machine for continuously and automatically printing calendar sheets in sequential order, comprising in combination a plurality of rotatable printing heads, each head carrying a series of 60 calendar data to be printed on said sheets differ-

ing from the data on the other heads, driving means associated with each of said heads and each having means corresponding to each of the data of the head with which they are associated, a plunger adapted to engage each of said driving means to rotate said heads one step at a time, means for driving said plungers, a chain having a link corresponding to each day of a year, means for moving said chain one link at a time, and means under the control of said chain for rendering predetermined strokes of predetermined plungers ineffective as to said driving means and printing heads associated therewith.

2. In a printing machine, means for automatically printing calendar sheets in proper sequential order comprising in combination a plurality of rotatable printing heads carrying a series of plates bearing differing data as to the months, weeks and days of a year, a ratchet wheel associated with each of said heads and having a tooth corresponding to each of said plates, a plunger arm adapted to engage each of said ratchet wheels to rotate its associated head one step at a time, means for operating said plunger arms, supports for said arms, bell-crank means for modifying the position of said supports to render predetermined strokes of said plunger arms effective or ineffective as to the ratchet wheels and printing heads associated therewith, chain means for operating said bell-crank means, and means for operating said chain means.

3. A calendar printing machine comprising in combination, printing means adapted for cooperation with paper upon which calendar indicia are to be printed, means for successively engaging the printing means and paper to effect successive printing operations on the paper, said printing means including indicia for a plurality of months having various numbers of days, and means indexed as an incident to each printing operation and having a position corresponding to each day of the calendar year and calibrated in accordance with the actual date sequence of dates within a year for causing the successive operation of each month indicia in accordance with the number of days in such month.

4. A calendar printing machine comprising in combination, printing mechanism adapted for cooperation with paper or the like upon which calendar indicia is to be printed, means for effecting successive engagement between the printing means and the paper to effect successive printing operations on the paper, said printing means including a sequence numbering mechanism for printing the dates within a plurality of calendar months having various numbers of days within the year, and means indexed as an incident to each printing operation and having a position corresponding to each day of the calendar year and calibrated in accordance with the actual date sequence within the calendar year for controlling the operation of said date printing means whereby to effect a plurality of sequential operations for a plurality of calendar months in accordance with the actual number of days in such calendar months.

5. A calendar printing machine comprising in combination, printing means adapted for cooperation with paper or the like upon which calendar indicia is to be printed, means for effecting successive engagement between the printing means and the paper to effect the printing of calendar indicia upon the paper, said printing means comprising indicia corresponding to a plurality of months having various numbers of days

within a calendar year and indicia for printing the date sequence with successive calendar months, and control means indexed as an incident to each printing operation for causing the repeated operation of the month indicia for a given month while simultaneously advancing the date indicia to effect the printing of successive dates within said month, and for thereafter effecting a change in the month indicia and the beginning of a new sequence of operation of the date indicia, said control means including a member directly connected to both the month indicia advancing means and the date indicia advancing means.

15 6. A calendar printing machine comprising in combination, printing means adapted for cooperation with paper or the like upon which calendar indicia is to be printed, means for effecting the successive engagement of the printing means and the paper to effect successive calendar printing operations, said printing means including number printing mechanism for printing the dates within a plurality of calendar months having various numbers of days within the year, means for successively advancing the number printing mechanism one number upon each operation of the printing means to effect sequential date printing within a given calendar month, and means indexed as an incident to each printing operation and having a position corresponding to each day of the calendar year and calibrated in accordance with the actual date sequence within a year for restoring said number printing mechanism to unity after the number corresponding to the actual days in said month has been reached.

7. A printing machine as defined in claim 6 wherein said number printing mechanism is provided with thirty-one numerical indicia and 40 wherein said restoring means comprising mechanism for rapidly advancing the number printing means through a plurality of numbers when the last day of said month has been reached and in the event said month comprises less than 45 thirty-one days.

8. A calendar printing machine comprising printing means adapted to engage paper on which calendar indicia is to be printed, means for successively engaging the printing means and paper to effect sequential printing operations, and control means indexed as an incident to each printing operation for controlling the printing means to effect printing operations in accordance with the actual date sequence of a calendar year having months of various numbers of days, collecting means, and means for transmitting the printed paper in sheet form to the collecting means, said control means being arranged to control the collecting means for stacking the sheets and separating successive pads.

9. In a machine for continuously and automatically printing a sequence of individual calendar indicia upon paper or the like, the combination of a plurality of shiftable printing heads 65 each carrying a series of calendar data to be printed on said paper, said data on each head differing from the data of the other heads, driving means associated with each of said heads and each driving means having mechanism corresponding to each of the data of the head with which it is associated, an actuator adapted to engage each of said driving means to operate said heads adjustably to shift said heads a predetermined amount, means for operating said actuators, and a control member having a series of 70 75

control means thereon corresponding to each day of a year, means for moving said control member a predetermined amount to correspond with each day of the year, and means under the control of said control member for rendering predetermined movements of selected actuators ineffective as to said driving means and printing heads associated therewith.

10. In a machine for printing and making complete calendar pads composed of individual superimposed, chronologically arranged sheets each bearing calendar indicia thereon, the combination of a bed, means thereon comprising an actuator for feeding a web of paper along a predetermined path on said bed, means operated in synchronism with the feed of the paper for printing thereon in spaced apart succession the consecutive dates of each day of each month of a calendar year having months of various numbers of days, said printing means including control mechanism indexed as an incident to each printing operation for automatically changing the number of the last day of each month to unity for the first day of the next succeeding month, means for cutting said web after printing thereon into individual daily sheets for the calendar pad, each sheet bearing one of said printed dates, and means controlled by said control mechanism for stacking the sheets and separating successive pads.

11. In a machine for continuously and automatically printing calendars each comprising individual calendar sheets corresponding to the days of a complete year, in combination a support, means for feeding paper along a predetermined path relative to said support, a plurality of rotatable printing heads mounted on said support, an actuator for feeding said paper, each head carrying a plurality of printing plates, each plate respectively carrying information relative to the dates of a year having months of various numbers of days, a structure shiftably mounted on said support of said machine for carrying said printing heads, operating means actuated on upward movements of said structure for moving certain of said printing heads in a direction to bring predetermined new plates into printing position relative to said paper, and control means indexed as an incident to each printing operation and having a position corresponding to each day of the calendar year for controlling the action of the operating means.

12. An automatic machine for printing and making yearly calendar pads comprising a bed, an actuator thereon for intermittently feeding paper therealong, a support mounted on said bed for shifting movement relative to the path of movement of said paper, means synchronized with the movement of the paper for shifting said support on said bed a plurality of printing heads shiftably mounted on said support, one of said heads having a set of printing surfaces corresponding to the twelve months of a year having months of various numbers of days, another of said heads having printing means adapted to print the days of the month, means operated by the actuator in synchronism with the movement of the paper and the shifting movement of the support for shifting said printing heads whereby to print upon said paper a succession of calendar data, each comprising the date of a calendar day of the year, and control means indexed as an incident to each printing operation and having a position corresponding to each day of the calendar year for automatically shifting the means for printing the dates to begin at unity when each printing

means for printing the month is shifted to print a succeeding month and for shifting the month printing means, whereby said data is printed on the paper in chronological sequence.

- 5 13. A calendar printing machine comprising printing means adapted to engage paper on which calendar indicia is to be printed, said printing means including a continuous sequence indexible means having plates in a multiple of seven for printing indications for the individual days of the week, means for successively engaging the printing means and paper to effect sequential printing operations, and control means indexed as an incident to each printing operation having an end of the year control element for controlling the printing means to effect printing operations in accordance with the actual date sequence of a calendar year, and thereafter in accordance with the date sequence of said same calendar year.
- 10 14. A calendar printing machine comprising printing means adapted to engage paper on which calendar indicia is to be printed, said printing means including means normally indexible a predetermined distance for printing indications for the individual days of the week, means for successively engaging the printing means and paper to effect sequential printing operations, and control means indexed as an incident to each printing operation for controlling the printing means to effect printing operations in accordance with the actual date sequence of a calendar year, and thereafter in accordance with the date sequence of said same calendar year. said control means including an end of the year control element for varying the normal indexing of the day of the week printing means to cause said means to print indications for the same day of the week on the printing operation for the last date of the calendar year, and on the printing operation for the succeeding first day of said calendar year.
- 15 15. A calendar printing machine comprising printing means adapted to engage paper on which calendar indicia is to be printed, said printing means including means normally indexible a predetermined distance for printing indications for the individual days of the week, means for successively engaging the printing means and paper to effect sequential printing operations, and control means indexed as an incident to each printing operation for controlling the printing means to effect printing operations in accordance with the actual date sequence of a calendar year, and thereafter in accordance with the date sequence of said same calendar year. said control means including an end of the year control element for varying the normal indexing of the day of the week printing means to cause said means to print indications for a given day of the week on the printing operation for the last date of the calendar year, and for the preceding day of the week on the succeeding printing operation for the first day of said calendar year.
- 20 16. A calendar printing machine comprising printing means adapted to engage paper on which calendar indicia is to be printed, said printing means including means for printing indications for the individual days of the week the dates of the month, and the months of the year, said day of the week printing means comprising continuous sequence indexible means having plates in a multiple of seven, means for successively engaging the printing means and paper to effect sequential printing operations, and control means indexed as an incident to each printing operation for controlling the printing means to effect printing op-

erations in accordance with the actual date sequence of a calendar year having months of various numbers of days, and thereafter in accordance with the date sequence of said same calendar year, said control means having an end of the year control element for controlling the operation of the day of the week printing means.

17. A calendar printing machine comprising printing means adapted to engage paper on which calendar indicia is to be printed, said printing means including a member for printing indications for the individual days of the week, a member for printing the dates of the month, and a member for printing the months of the year, each of said members being separately indexible and said day of the week printing member comprising a continuous sequence indexible member having plates in a multiple of seven, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means having an end of the year control element for controlling the operation of the day of the week printing member.

18. A calendar printing machine comprising printing means adapted to engage paper on which calendar indicia is to be printed, said printing means including means for printing indications for the individual days of the week, the dates of the month, and the months of the year, means for successively engaging the printing means and paper to effect sequential printing operations, control means indexed as an incident to each printing operation for controlling the printing means to effect printing operations in accordance with the actual date sequence of a calendar year having months of various numbers of days, and thereafter in accordance with the date sequence of said same calendar year, and stacking means for the printed paper, said stacking means being controlled by said control means to effect demarcation of successive year pads.

19. A calendar printing machine comprising

printing means adapted to engage paper on which calendar indicia is to be printed, said printing means including a member for printing indications for the individual days of the week, a member for printing the dates of the month, and a member for printing the months of the year, each of said members being separately indexible, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means including means for shifting the date of the month printing member to unity simultaneously with each shifting of the month printing member, and for causing the day of the week printing member to repeat a printing operation for the same day of the week as the month printing member is shifted from December to January.

20. A calendar printing machine comprising printing means adapted to engage paper on which calendar indicia is to be printed, said printing means including a member for printing indications for the individual days of the week, a member for printing the dates of the month, and a member for printing the months of the year, each of said members being separately indexible, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means including means for shifting the date of the month printing member to unity simultaneously with each shifting of the month printing member, and for causing the day of the week printing member to retract one step as the month printing member is shifted from December to January.

JOHN C. WAHL

CERTIFICATE OF CORRECTION.

Patent No. 2,366,300.

January 2, 1945.

JOHN C. WAHL.

It is hereby certified that error appears in the printed specification of the above numbered patent requiring correction as follows: Page 1, second column, line 35, for "actutaing" read --actuating--; page 7, first column, line 24, for "serves" read --severs--; and that the said Letters Patent should be read with this correction therein that the same may conform to the record of the case in the Patent Office.

Signed and sealed this 27th day of March, A. D. 1945.

Leslie Frazer

(Seal)

Acting Commissioner of Patents.

erations in accordance with the actual date sequence of a calendar year having months of various numbers of days, and thereafter in accordance with the date sequence of said same calendar year, said control means having an end of the year control element for controlling the operation of the day of the week printing means.

17. A calendar printing machine comprising printing means adapted to engage paper on which calendar indicia is to be printed, said printing means including a member for printing indications for the individual days of the week, a member for printing the dates of the month, and a member for printing the months of the year, each of said members being separately indexible and said day of the week printing member comprising a continuous sequence indexible member having plates in a multiple of seven, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means having an end of the year control element for controlling the operation of the day of the week printing member.

18. A calendar printing machine comprising printing means adapted to engage paper on which calendar indicia is to be printed, said printing means including means for printing indications for the individual days of the week, the dates of the month, and the months of the year, means for successively engaging the printing means and paper to effect sequential printing operations, control means indexed as an incident to each printing operation for controlling the printing means to effect printing operations in accordance with the actual date sequence of a calendar year having months of various numbers of days, and thereafter in accordance with the date sequence of said same calendar year, and stacking means for the printed paper, said stacking means being controlled by said control means to effect demarcation of successive year pads.

19. A calendar printing machine comprising

printing means adapted to engage paper on which calendar indicia is to be printed, said printing means including a member for printing indications for the individual days of the week, a member for printing the dates of the month, and a member for printing the months of the year, each of said members being separately indexible, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means including means for shifting the date of the month printing member to unity simultaneously with each shifting of the month printing member, and for causing the day of the week printing member to repeat a printing operation for the same day of the week as the month printing member is shifted from December to January.

20. A calendar printing machine comprising printing means adapted to engage paper on which calendar indicia is to be printed, said printing means including a member for printing indications for the individual days of the week, a member for printing the dates of the month, and a member for printing the months of the year, each of said members being separately indexible, means for successively engaging the printing means and paper to effect sequential printing operations, and control means indexed as an incident to each printing operation for controlling the printing means to effect printing operations in accordance with the actual date sequence of a calendar year having months of various numbers of days, and thereafter in accordance with the date sequence of said same calendar year, said control means including means for shifting the date of the month printing member to unity simultaneously with each shifting of the month printing member, and for causing the day of the week printing member to retract one step as the month printing member is shifted from December to January.
